INTERNAL COMBUSTION ENGINE

Irving E. Aske, Muskegon, Mich., assignor to
Campbell Wyant and Cannon Foundry Com-
pany, Muskegon Heights, Mich., a corporation
of Michigan

Application July 23, 1934, Serial No. 736,477

2 Claims. (Cl. 123—173)

This invention relates to internal combustion engines, and particularly to such engines wherein a combustible charge composed of air and a fuel vapor is compressed in the working cylinder and combustion chamber of the engine, which combustion chamber is usually situated in the cover of the cylinder and while compressed, the combustible charge ignited.

The invention has for its objects, first, an improved transfer of heat generated by the burning charge of fuel in the cylinder and combustion chamber to the circulating medium surrounding the cylinder barrel and combustion chamber; second, to increase the power output of the engine for a given unit of fuel consumed; third, to minimize detonation within the engine; and, fourth, a general improvement in the efficiency of the engine.

These objects and other more specific objects hereinafter appearing are attained by, and the invention finds preferable embodiment in the hereto attached specification and description, and as illustrated by the accompanying drawing, in which:

Fig. 1 is a view of the under side of a portion of a cover showing a heat transfer insert in position.

Fig. 2 is a sectional view taken on line X of Figure 1.

Fig. 3 is a perspective view of the heat transfer insert.

Fig. 4 is a perspective view of the bonding washer before the heat transfer insert has been cast onto it.

In the drawing similar characters refer to similar parts throughout the several views.

1 represents a cylinder cover of an internal combustion engine; 2 the combustion chamber and 3 that portion of the cover that lies directly over the cylinder bore. 4 is the heat transfer insert, provided with a bonding washer 5. The insert which is preferably made of copper or other like material is provided with serrations 6 whereby the maximum area of the insert is presented to the circulating cooling medium. The heat transfer insert is preferably made in the form shown, having a flat head portion 7 presented to the hot flame of combustion and a neck portion 9. The circulating cooling medium is contained in the chamber 10. 11 represents a conventional spark plug by which the compressed charge may be ignited. This spark plug may be dispensed with in Diesel engines.

In considering the objects of this invention, it is well known among combustion engineers that

a higher compressed combustible charge than is ordinarily possible is desired in order to obtain a higher power output than heretofore with the usual compressed charge, but when the charge is compressed to six or more ratios, a severe detonation takes place within the engine and it is therefore not practical to employ compression ratios greater than six without these detonation knocks unless provision is provided whereby the burning of the charge as a whole is slowed; or a means whereby the transfer of heat generated by the burning charge is made more rapid than through cast iron as usually employed for the covers of the cylinder and walls of the combustion chamber. Aluminum cylinder covers have been made and employed. These aluminum covers answered fairly well for transferring the heat of combustion to the cooling medium circulated through the cover chamber but they would not stand the strains imposed when the engine was operating under near full load output for a considerable period of time. In the present invention copper or its equivalent in heat conduction is employed which, it was found, could not be adequately joined directly to the cast iron of the cover when the copper heat transfer insert was placed in the mold and the cover cast onto it therefore. The bonding washer 5 is provided and the heat transfer insert cast onto and bonded to it. Then the insert is placed in the mold in which the cover is to be cast and the molten iron to form the cover run into the mold and onto the heat transfer insert and bonding washer. By this method it is found when the bonding washer is of steel or the like, the heat transfer insert of copper or copper alloy and the cover of cast iron a perfect bond is obtained between the heat transfer insert and the bonding washer, also between the bonding washer and the cast iron of the cover and that a light, unbreakable joint is obtained between the chamber in the cover and the face of the cover. It has been found that with covers constructed in accordance with this invention that compression ratios of nine and even ten to one are possible and that a considerable increase in power without detonation is obtained over the usual construction of internal combustion engine.

What is claimed, is:

1. A cylinder head for internal combustion engines, the said head comprising a body having a face for closing the end of the cylinder, a cooling fluid chamber in spaced relation to the said face, a heat transfer member extending from said face into the said cooling fluid chamber and a washer- 55

like member embedded into the wall of the body between the said face and the cooling fluid chamber and into the exterior of the heat transfer member for the purpose specified.

5 2. In a cylinder cover for internal combustion engines, the said cover having a face for closing

the end of the cylinder and a cooling fluid chamber, a heat transfer member secured to the cover between the said face and the cooling fluid chamber by a washer embedded into the heat transfer member and into the metal of the cover.

IRVING E. ASKE. 5
